UNITED STATES PATENT OFFICE.

JABEZ S. SNOW, SR., OF SCHUYLER, VIRGINIA.

OIL CUP.

Application filed March 25, 1925. Serial No. 18,209.

This invention aims to provide novel means for lubricating machinery of any kind, regardless of whether the oil cup is fixed or movable.

5 It is within the province of the disclosure to improve generally and to enhance the utility of devices of that sort to which the invention appertains.

Although preferred forms have been 10 shown in the drawings, it will be understood that a mechanic, working within the scope of what is claimed, may make such changes as his skill may suggest, without departing from the spirit of the invention.

15 In the accompanying drawings:—

Figure 1 shows in longitudinal section, a device constructed in accordance with the invention, parts being in elevation; Figure 2 is a transverse section on the line 2—2 of 20 Figure 1; Figure 3 is an elevation showing a slight modification in the valve; Figure 4 is a fragmental longitudinal section showing a modification in the device delineated in Figure 1; and Figures 5 and 6 are sectional 25 views illustrating modifications in that form of the invention which is illustrated in Figure 4.

Referring particularly to Figures 1 and 2, there is shown a cup 1, adapted to contain a 30 lubricant, and including a receptacle 2 having a neck 3 which is externally threaded as at 4 for engagement with the part to be lubricated, there being a wrench shoulder 5 at the place of juncture between the neck 3 and the cup 1, so that the cup may be turned readily to thread it into place. In the lower end of the neck 3 there is a recess 6 communicating with a reduced bore 7 which, at its upper end, communicates, with 35 a flared seat 8 formed in the bottom of the receptacle 2. A closure 9 for the receptacle 2 is provided, and may be in the form of a cap having a marginal flange 10 threaded at 11 on the receptacle 2, the closure 9 having 40 a wrench lug 12 whereby it may be rotated readily. The closure 9 carries a fixed inwardly extended stem 14, which is inaccessible when the closure 9 is mounted on the receptacle 2.

45 The numeral 15 designates a valve including a body 16 having a reduced stem 17, the body 16 having a tapered end 18 adapted to fit in the seat 8. The stem 17 of the valve 15 is mounted to reciprocate in the bore 7, and is supplied with longitudinal grooves 19.

The device shown in Figure 1 of the draw-

ings and above described is adapted to be mounted on some piece of machinery which moves. The valve 15 is located below the stem 14 of the closure 9 and is spaced slightly 60 therefrom. As the piece of machinery which carries the cup 1 moves, the valve 15 will move upwardly and downwardly, the part 18 of the valve moving to and from the seat 8, thereby permitting the lubricant to pass 65 from the receptacle 2 through the grooves 19 to the part to be lubricated.

When it is desired that the part to be lubricated shall have an increased supply of oil, then the valve 15 is replaced by the 70 valve 20 of Figure 3, the valve 20 comprising a body 21 having a tapered end 22, the stem being designated by the numeral 23 and the numeral 24 marking the grooves in the stem. It is to be observed that the body 75 21 of the valve 20 is shorter than the body 16 of the valve 15. Consequently, the valve 20 will have an increased amount of play to and from the end of the part 14. There may be as many valves as desired, the valves 80 having heads of different lengths. By substituting one valve for another, the amount of lubricant delivered may be regulated.

In devices of the class described, as hitherto constructed, it has been the common practice to limit the movement of such a part as the valve 15, adjustably, through the instrumentality of a screw threaded for adjustment into such an element as the cap 9. The disadvantage incident to the use of an adjusting screw is that, after one person who understands thoroughly the amount of lubricant that should be delivered to any part, has made an adjustment, some other person, whose judgment is not to be relied upon, moves the adjusting screw and a heated or burned out bearing is the result. In the device forming the subject matter of this application, the adjustment is obtained, not by rendering the stem 14 longitudinally adjustable, but, rather, by substituting one valve for another, the valves having heads of different lengths, as illustrated in the parts 16 and 21. A person expert in lubrication, and well advised as to the amount of lubricant required by any particular bearing, sets up the device as shown in Figure 1, and there it remains, there being no adjusting screw to be tampered with.

110 It has been stated hereinbefore that the article shown in Figure 1 is adapted to be used on some machine part which has a

movement. In the event that it is desired to use the device on a machine part which has no movement, that is, upon a "dead bearing" when recourse may be had to the structure shown in Figure 4. In that figure, parts hereinbefore described have been designated by numerals previously used, with the suffix "a".

The valve is marked by the numeral 25 and includes a body 26 and a stem 27, the groove in the stem being shown at 28. The groove is extended laterally across the lower end of the body 26 of the valve 25, to permit the passage of lubricant, because the oil cup itself has no movement. Such a valve as the valve 25 may be replaced by the valve 30 of Figure 5, the body of the valve 30 being designated by the numeral 31, the stem being shown at 32, the groove at 33, and the extension at 34. The grooves 33-34 are deeper than the corresponding elements 28-29, and by substituting such a part as the valve 30 for the valve 25, an increased flow of oil may be afforded.

In Figure 6, the valve 30 is shown at 36²⁵ and includes a body 37 and a stem 38, the stem having grooves 39 on both sides, these grooves being extended, as shown at 40, along the lower surface of the body 37.

Having thus described the invention, what is claimed is:—

1. In a lubricator of the class described, a receptacle, a closure for the receptacle, a stem of determined length fixedly and rigidly secured to the closure and housed completely within the receptacle, the receptacle having an outlet for lubricant, and a valve slidably mounted in the receptacle in substantial alinement with the stem, the valve controlling the outlet. ⁴⁰

2. A lubricator of the class described, constructed as set forth in claim 1, and further characterized by the provision of means whereby the valve may be spaced at variable distances from the inner end of the stem. ⁴⁵

In testimony that I claim the foregoing as my own, I have hereto affixed my signature.

JABEZ S. SNOW, Sr.
